CHARLES H. EMERY, OF RACINE, WISCONSIN, ASSIGNOR TO HARTMANN TRUNK COMPANY, OF RACINE, WISCONSIN, A CORPORATION OF WISCONSIN

CONTAINER-COVER STAY

Application filed May 31, 1929. Serial No. 367,374.

This invention relates to improvements in container cover stays.

Containers, hat boxes, and pieces of luggage, in which a cover is hinged connected to the body, are usually provided with flexible straps or strips extended between inner side portions of the body and inner side portions of the cover, said strips being for the purpose of preventing the cover from being opened too far and holding it in a tilted open position. Difficulty is encountered with these strips, however, in closing the container, as the strips are elongated, and when the cover is closed said strips break or fold medially, and the tendency is for the folded portions thereof to project outwardly between the valances of the container, and outwardly of the container, and the same prevent a perfect closure of the container sections and are unsightly when projecting out of the closed container.

It is, therefore, the primary object of the present invention to provide container cover stays arranged so as to always fold or break inwardly of the confines of the container, when the cover is closed, so as to be completely confined.

A further object of the invention is to provide container cover stays constructed with a partial rigid reinforcement to influence the same in breaking or folding interiorly of a container when the cover to which they are attached is moved to closed position.

A further object of the invention is to provide container cover stays which are inexpensive to manufacture, and with which a container or piece of luggage may be readily equipped.

A further object of the invention is to provide a container cover stay which is of very simple construction, is strong and durable, and is well adapted for the purposes described.

With the above and other objects in view, the invention consists of the improved container cover stay, and its parts and combinations as set forth in the claims, and all equivalents thereof.

In the accompanying drawing, in which

the same reference characters indicate the same parts in all of the views:

Fig. 1 is a side view of a container with its cover in open position with the improved stays connected between the cover and inner portions of the side walls of the container body;

Fig. 2 is an enlarged fragmentary view, partly in vertical section, of a wardrobe case provided with the improved cover stays, there also being a dotted line showing of the cover and stays when the former is in open position;

Fig. 3 is a fragmentary detail sectional view taken on line 3-3 of Fig. 2;

Fig. 4 is an enlarged detail front view of a cover stay with part broken away and in section; and

Fig. 5 is a vertical sectional view of the cover stay.

Referring now more particularly to the drawing it will appear that the numeral 8 indicates a piece of hand luggage or case having a body section 9 closed by a pair of hinged covers 10. Within one of the compartments 75 of the body section is a removable tray 11 mounted on side rails 12. The invention relates particularly to the cover stays, and, as they are identical, only one stay will be described in detail although it is understood 80 that each cover is preferably fitted with a pair of opposite stays.

The improved stay is indicated by the numeral 13, and it comprises an elongated narrow strip formed of two plies of fabric 14 85 sewed together. There is interposed between the layers, extending from an end portion inwardly a substantial distance, a reinforcing element 15 formed of band steel, or some other thin material which will give rigidity 90 to a substantial length of the stay.

As shown in Figs. 1 and 2, each stay is fastened at its opposite end portions by means of tacks or brads 16 inserted through eyeleted openings 17, respectively to an inner side wall of the cover inwardly of its inner end, and to an inner side wall of the body inwardly of its edge or valance. As shown, particularly in Fig. 2 the reinforced end portion of the stay is the end portion of 100

the stay adjacent the side of the body, and said reinforced stay portion is of a sufficient length to extend a substantial distance beyond the edge or valance of the body side wall, terminating a trifle above the upper edge of the tray 11 when it is in position.

With the improved cover stays, when the cover is opened the stays function in their usual manner, as shown in Fig. 1. However, 10 when the cover is closed, the reinforced portion of the stay, because it extends beyond the joint of the cover and body into the cover, will cause the flexible portion of the stay to break or fold immediately above the end of the reinforcing element, and the folded portions of 15 the stay will be disposed inwardly of the confines of the container or case, (this being the only direction in which it can fold), as shown in Figs. 2 and 3, whereby the case will close 20 properly and the objection of outwardly projecting stay portions is eliminated. The folded portions of the stay are not sufficiently long to extend to the joint of the cover and body.

25 From the foregoing description it will be seen that the improved container cover stay is both simple and novel, and is well adapted for the purposes described.

What I claim as my invention is:

30 1. The combination with a container having a body section and a cover hinged thereto, of a cover stay extended between inner portions of the cover and body section, said stay having a rigid portion extending substantially 35 beyond the meeting edge portions of the cover and body section and a flexible portion adjacent the extending end of the rigid portion.

40 2. The combination with a container having a body section and a cover hinged thereto, of a cover stay extended between inner portions of the cover and body section remote from the outer edges thereof, a portion of said stay extending from one section into the other 45 having rigidity and the remainder thereof being flexible to cause a breaking and folding of the stay inwardly of the confines of the container when the cover is closed.

50 3. The combination with a container having a body section and a cover hinged thereto, of an elongated strip forming a cover stay extended between inner side walls of the cover and body section, said stay having a reinforced portion extending from a side wall 55 substantially beyond the meeting edge portions of the cover and body section and a flexible portion extending from the reinforced portion to the other side wall, said flexible portion when folded upon itself being of less 60 length than the distance from the outer end of the reinforced portion to the meeting edge portions of the cover and body section.

65 4. The combination with a container having a body section and a cover hinged thereto, of an elongated strip forming a cover stay

extended between inner side walls of the cover and body section, said stay having a considerable portion of its length reinforced so as to be rigid with said reinforced portion extending from a side wall of the body section substantially beyond its outer edge, and the remainder of the stay being readily foldable.

In testimony whereof, I affix my signature.

CHARLES H. EMERY.
